Des. 224,143

Patented July 4, 1972

224,143

VEHICLE AUXILIARY LAMP

Douglas R. Cleminshaw and Robert G. Wells, Syracuse,
N.Y., assignors to R. E. Dietz Company, Syracuse,
N.Y.

Filed Sept. 15, 1970, Ser. No. 24,999

Term of patent 14 years

Int. Cl. D26—06

U.S. Cl. D48—32

Fig. 2

Fig. 1

Des. 224 143

PAGE 3

FIG. 1 is a front elevational view of a vehicle auxiliary lamp embodying our new design;

FIG. 2 is a top plan view thereof;

FIG. 3 is a side elevational view thereof, the other side being a mirror image thereof;

FIG. 4 is a bottom plan view thereof;

FIG. 5 is a front elevational view of a second embodiment of our new design;

FIG. 6 is a top plan view thereof;

FIG. 7 is a side elevational view thereof, the other side being a mirror image thereof; and

FIG. 8 is a bottom plan view thereof.

The indicia is shown in broken lines in FIGS. 1 and 5 for illustrative purposes only.

We claim:

The ornamental design for a vehicle auxiliary lamp, substantially as shown and described.
